UNITED STATES PATENT OFFICE.

GEORGE F. CLARK, OF UTICA, NEW YORK.

DESIGN FOR A SPRAYER-BODY.

SPECIFICATION forming part of Design No. 34,016, dated January 29, 1901.

Application filed January 7, 1901. Serial No. 42,459. Term of patent 3½ years.

To all whom it may concern:

Be it known that I, GEORGE F. CLARK, a citizen of the United States, residing at Utica, in the county of Oneida and State of New York, have invented and produced a new and original Design for the Body of a Sprayer, of which the following is a specification, reference being had to the accompanying drawing, forming a part thereof.

10 The drawing shows a perspective view of a sprayer of my new design.

The feature of the design is the form and relative arrangement of the parts forming the sprayer-body—that is to say, having an elongated cylinder portion 1 and a large short cylinder portion 2, arranged under one end and

parallel with the cylinder 1, one end projecting beyond the cylinder 1, substantially as shown.

Having described my invention, what I claim as new, and desire to secure by Letters Patent, is—

The design for a sprayer-body, as herein shown and described.

In witness whereof I have hereunto signed my name, in the presence of two witnesses, this 31st day of December, 1900.

GEO. F. CLARK.

Witnesses:

S. A. BROWN,
CHARLES G. IRISH.
